CLAIM

The ornamental design for a splashless liquid pouring container, as shown and described.

DESCRIPTION

FIG. 1 is a front elevational view of the splashless liquid pouring container showing our new design;

FIG. 2 is a side elevational view thereof, the opposite side being a mirror image thereof;

FIG. 3 is a rear elevational view thereof;

FIG. 4 is a top plan view thereof;

FIG. 5 is a bottom plan view thereof;

FIG. 6 is a view along the plane of line 6—6 looking in the directions of the arrows;

FIG. 7 is a view along the plane of line 7—7 looking in the direction of the arrows;

FIG. 8 is a front elevational view of a modification of the splashless liquid pouring container showing our new design;

FIG. 9 is a side elevational view of FIG. 8, the opposite side being a mirror image thereof;

FIG. 10 is a rear elevational view of FIG. 8;

FIG. 11 is a top plan view of FIG. 8; and,

FIG. 12 is a bottom plan view of FIG. 8.
